COMBINED DISPLAY AND STORAGE TRAY FOR FLATWARE OR THE LIKE

Samuel Braun, Rye, N.Y., assignor to B.C.N. Design
Products, Inc., Amityville, N.Y., a corporation of
New York

Filed Dec. 14, 1967, Ser. No. 9,785

Term of patent 14 years

U.S. Cl. D80—9

Int. Cl. D7—01

FIG. 1

FIG. 2

FIG. 1 is a top plan view of a combined display and storage tray for flatware or the like embodying my new design;

FIG. 2 is a front elevational view thereof;

FIG. 3 is a bottom plan view thereof;

FIG. 4 is an end elevational view thereof;

FIG. 5 is a perspective view thereof;

FIG. 6 is a fragmentary top plan view of one end thereof; and

FIG. 7 is a fragmentary cross sectional view taken on line 7-7 of FIG. 1.

I claim:

The ornamental design for a combined display and storage tray for flatware or the like, as shown.
